UNITED STATES PATENT OFFICE.

NATHANIEL BUTTERFIELD, OF MONROE, WISCONSIN.

FIRE-ESCAPE OR CHAIN LADDER.

SPECIFICATION forming part of Letters Patent No. 449,518, dated March 31, 1891.

Application filed November 20, 1890. Serial No. 372,095. (No model.)

To all whom it may concern:

Be it known that I, NATHANIEL BUTTERFIELD, a citizen of the United States, residing at Monroe, in the county of Green and State of Wisconsin, have invented a new and useful Fire-Escape, of which the following is a specification.

This invention relates to improvements in fire-escapes.

10 The object of the present invention is to simplify and improve the construction of chain ladders for fire-escapes and other purposes and provide convenient means for attaching the upper end of the ladder to a window-sill or the like.

15 The invention consists in the construction and novel combination and arrangement of parts hereinafter fully described, illustrated in the accompanying drawings, and pointed out in the claim hereto appended.

20 In the drawings, Figure 1 is a front elevation showing the ladder applied in operative position to a window-sill. Fig. 2 is a detail portion of the chain ladder. Fig. 3 is a detail 25 perspective view of the means for securing the ladder to a window-sill. Fig. 4 is a detail section on line $\alpha\alpha$ of Fig. 1.

25 Referring to the accompanying drawings, 1 designates a chain ladder composed of the chains 2, having links 3, provided with a pair 30 of loops 4, arranged in planes at right angles to each other, and flat rounds 5, constructed of flat metal and provided at their ends with perforations which receive the links at the narrow portions or necks 7 between the loops of the links, whereby the rounds are securely held at the desired point along the chains. The lower end of the chain is attached to a

reel or drum 8, composed of a rod 9, passing through the lowermost loops of the chains and 40 disks or flanges 10, and the chain ladder when not in use is wound upon the drum or reel. The chain ladder is secured to a window-sill by a rod 12, passing through the uppermost loop of the chains and provided at intervals 45 with clips 13, which are approximately U-shaped and provided at one end with an eye 14, adapted for the reception of the rod, and at the other end with a set-screw 15, arranged to engage the lower face of the sill. The rod 50 12 is rigidly secured in the eyes 14 of the clips, and the clips are arranged at the ends of the rod and at a point intermediate of its ends.

It will be seen that the chain ladder is simple and inexpensive in construction, and the 55 rounds are secured at the desired points without liability of accidentally slipping, and that simple and inexpensive means are provided for securing the ladder to a window-sill or the like.

60 What I claim is—

The combination, with a chain ladder, of the rod 12, passing through the links, and the approximately U-shaped clips arranged at intervals on the rod and provided at one end 65 with eyes to receive the rod and provided at the other end with set-screws adapted to engage a window-sill or the like, substantially as described.

In testimony that I claim the foregoing as 70 my own I have hereto affixed my signature in presence of two witnesses.

NATHANIEL BUTTERFIELD.
